UNITED STATES PATENT OFFICE.

EMERY E. HARDY, OF BAYSIDE, NEW YORK.

ROLLER-SKATE.

1,152,813.

Specification of Letters Patent.

Patented Sept. 7, 1915.

Application filed July 25, 1914. Serial No. 853,060.

To all whom it may concern:

Be it known that I, EMERY E. HARDY, a citizen of the United States, residing at Bayside, in the county of Queens and State of New York, have invented certain new and useful Improvements in Roller-Skates, of which the following is a specification.

My invention relates to improvements in roller skates, and the object of my improvement is simplicity and economy in construction and convenience and efficiency in use.

In the accompanying drawings: Figure 1 is a side elevation of my improved roller skate. Fig. 2 is an end elevation of the same. Fig. 3 is an elevation of the other end. Fig. 4 is a plan view of the same. Fig. 5 is a bottom view of the same. Fig. 6 is a bottom view, with the wheels removed, and the parts adjusted to a different position. Fig. 7 is a sectional view on the line *x-x* of Fig. 4. Fig. 8 is a sectional view on the line *y-y* of Fig. 1. Fig. 9 is a sectional view on the line *z-z* of Fig. 1. Fig. 10 is a bottom view, showing the two parts of the body portion partially disengaged. Fig. 11, sheet 1, is a side elevation of the front wheel. Fig. 12, sheet 1, is a sectional view of the same on the line *u-u* of Fig. 11. Fig. 13 is a plan view of the sole member. Fig. 14 is a similar view of the heel member. Fig. 15 is a plan view of the blank for the front heel lug member.

My improved roller skate comprises a body portion made up of a sole member 10 at the front end and a heel member 11 at the rear end, which members are separably and adjustably connected together in a manner to be described and which are provided with roller or wheel devices and supporting means therefor that are of special character. The sole member 10 is provided with a single wheel 12 and the heel member 11 with a pair of wheels 13, the latter being of the same diameter, and separated by an appreciable space.

I prefer to make the front wheel 12, on the sole member 10, of appreciably greater diameter, as shown, than the rear wheels 13, on the heel member 11, and to extend the supporting means for the rear wheels 13 to compensate for the difference in the diameters, so that the tread portions that engage with the floor or ground will be at about the same distance from the body portion. I also provide an adjustable front heel lug 14 that engages with the front wall of the

heel, below the instep, and which coöperates with a fixed rear heel lug 15 that engages with the rear wall of the heel and which is provided at the rear end of the heel member 11. Lateral strap lugs 16 are provided at the sides of the heel member 11, having slots 17 for straps. I prefer to have the said strap lugs 16 pivotally connected to the heel member 11, as by a pivotal pin 18, so as to swing in a horizontal plane. The sole member 10 is provided with securing means 19 for securing the front end of the skate to the sole of the shoe which are ordinary, except that I provide slots 20 for straps in the up-turned lug member 21. That is to say, the lug member 21 is of the usual form for engaging the sole of the shoe, involving a curling over inwardly of the upper or tip end as shown and in addition thereto is provided with the bar 75 as shown for the strap that is separated from the adjacent body portion of the lug member 21 by the strap receiving slot 20. This permits of freely connecting the strap to the lug member 21 without interfering 80 with the usual and ordinary operation of the securing means 19, so that the strap can be used independently of and in addition to said securing means 19.

The interconnecting of the sole member 85 and the heel member is effected in the following manner: The sole member 10 is provided with a rearwardly directed extension 22 and the heel member with a forwardly directed extension 23, which extensions overlap one another, the extension 22, on the sole member, overlying the extension 23 on the heel member. The extension 22 is bifurcated, comprising a pair of lateral members 24, separated by a slot 25 that is open at the 95 free ends of the said members. Adjacent the closed end of the slot 25 there is a headed stud 26, secured to the body portion of the sole member 10, the head 27 thereof being on the lower side and separated from the 100 said body portion by sufficient distance to permit of sliding engagement therewith of the walls of the slot 28 in the extension 23 when positioned between the said head 27 and the said body portion. The head 27 is 105 rectangular in shape, the greater dimension thereof being positioned crosswise, or at right angles to the direction of the slot 28 when in normal position, and the smaller dimension is a fit for the slot 28, suitably to 110 permit free engagement and disengagement of the heel member 11 therewith when the

same is turned at right angles to the said normal position. Accordingly, the sole member 10 and the heel member may be connected and disconnected when turned at 5 right angles, the one to the other.

The slots 25 and 28 are in registration, under normal conditions, and the stud 26 is in line therewith, and the locking means that I provide is positioned in the said slots, so 10 that the members 10 and 11 may be adjusted longitudinally to any position desired and secured by the said locking means. As shown, the said locking means comprises a bolt 29 and wing nut 30. I utilize the same 15 locking means, as described, to secure the front heel lug 14 in its adjusted position and do this in the following manner: The said front heel lug 14 consists of an upwardly directed extension of the front heel lug member 31, the body portion of which lies 20 along the upper side of the lateral members 24. The said body portion has a longitudinal slot 32 extending along the rear portion and adjacent the front end of the said 25 slot and in line therewith is a hole for the bolt 29. In the heel member 11 is secured a headed stud 33 that engages with the slot 32. In the front heel lug portion 14 of the member 31 there is provided a crosswise slot 30 34, at the lower portion thereof, which slot is in communication with the longitudinal slot 32, and which permits the head of the headed stud 33 to pass therethrough, so that the front heel member can be disengaged 35 therewith by drawing the same a sufficient distance forwardly. The blank for the front heel lug member 31 is shown in Fig. 15, the same in the final form being bent at about 40 right angles approximately along the broken line 60 shown in the said figure so that the front heel lug portion 14 thereof will be standing relatively to the body portion. The members 10 and 11 are normally held together by the bolt 29 passing through the 45 slots 25 and 28 and the nut 30, and when the nut 30 is loosened slightly the members 10 and 11 are free to move relatively the one to the other. Accordingly, when loosely connected as described in case the skate is lifted 50 by one of the members 10 and 11 and the other is in pendent position the lowermost of the said members would drop. Actual separation of the members is however prevented because the slot 28 is a closed slot, 55 the end wall of which would engage with the stud 26 and thereby limit the longitudinal movement of the members 10 and 11. In order to effect a separation of the members 10 and 11 the clamping screw must be removed from engagement therewith and the 60 members turned 90 degrees, as shown in Fig. 10, so as to bring the slot 28 of the member 11 in registration with the longer dimension of the rectangular head of the stud 27 65 and thereby permit the free disengagement

and engagement of the said slot and head. Back of the headed stud 33 the heel member 11 is provided with a crosswise slot 35 through which pass the free ends of the lateral members 24 of the sole member 10 70 when adjusted to the shorter lengths, the extreme ends thereof being thus housed on the under side of the body portion of the heel member 11. On the under side of the sole member 10 is secured a U-shaped member 75 that serves as the support for the front wheel 12 and on the heel member 11 is secured a second U-shaped member 37 which serves as the support for the rear wheels 13. In each case the said U-shaped member comprises a yoke portion which serves as the connecting means that is secured to the body portion of the particular member with which it is connected and a pair of side arms, slots 80 are provided in the side arms, and a shaft is 85 positioned in the slots, and the said shaft is held in its proper position by means consisting of a pair of washers 38 mounted on the said shaft and positioned in abutment with the side arms, on the outer faces thereof, and stop lugs 39 formed by bending outwardly the extreme end portions of the said side arms, there being a pair of such lugs, one on each side of the slot. 90

The side arms 40 referred to that are provided on the front wheel supporting member 36 are approximately vertical and also slots 41 provided therein. The side arms 42 on the rear wheel supporting member 37 are curved rearwardly, and the slots 43 therein are rearwardly directed to a slight extent. Furthermore, the arms 42 have sufficient extra length as compared with the arms 40 to compensate for the excess in diameter of the front wheel 12 over that of the rear 105 wheels 13, as has been mentioned. The front arms 40 are spaced apart to receive therebetween the front wheel 12, which is mounted on the front shaft 44 by means of ball bearings. The rear wheels 13 are mounted 110 on the ends of the rear shaft 45, which ends extend beyond the arms 42. The said arms 42 are spaced apart according to the spread desired for the two rear wheels 13 and are maintained in proper position by means of 115 a spacing tube 46 mounted on the middle portion of the shaft 45. I prefer to have the shaft 45 and the spacing tube 46 fixedly connected, as by providing a notch 47 in the shaft, at about the middle portion, and suitably indenting the tube, as shown at 48. The shafts 44 and 45 are provided with screw threads from the ends inwardly suitably to receive certain ball bearing parts that are mounted thereon, and securing devices therefor, and securing devices for locking the shafts in their proper positions in the slots 120 41 and 43 in the side arms 40 and 42.

In the case of the front wheel 12 and shaft 44, the wheel 12 is at the middle of the shaft, 130

and the portion of the wheel adjacent the hole for the shaft is formed on each side suitably to serve as a raceway 50 for balls 51 for the ball bearings, and the cones 52 that coöperate therewith are secured against the inner faces of the arms 40 by clamping nuts 53 on the outer faces thereof. Interposed between the said nut 53 and the arms 40 is the washer 38 that also serves as the 10 positioning washer for positioning the shaft by reason of its engagement with its periphery edge with the outwardly turned lugs 39 on the said arms as has been described. It will be noted that the said positioning 15 washer 38 also serves as a finishing washer, being of sufficient size to cover the slotted outer end portion of the arms 40, except for the lug portions 39 thereof.

In the case of the rear wheel portion the 20 positioning washers 38 are positioned on the inner sides of the wheels 13, the arms 42 being clamped against the spacing tube 46 by the nuts 54 on the shaft 45 and with the positioning washers between the same and the 25 said arms 42, and with the edges of the washers in engagement with the lugs 39. It will be noted that the nuts 54 also serve as cones for ball bearings, the outer faces 55 thereof being formed suitably for a raceway 30 for the balls 56 for the ball bearings 57 for the rear wheels 13. The parts of the ball bearings 57 for the rear wheels 13 are ordinary. The wheels 12 and 13 except for differences in size are similarly constructed. 35 The front wheel 12 is shown in Figs. 11 and 12, and comprises two similar mating members 59 held together by a plurality of rivets 60. The said wheel members 59 have inwardly directed flanges 61 at the periphery 40 that combine to form the tread of the wheel and at the middle are suitably shaped to form the raceway 50 already mentioned.

It is apparent that some changes from the specific construction herein disclosed may be 45 made and therefore I do not wish to be understood as limiting myself to the precise form of construction shown and described, but desire the liberty to make such changes, in working my invention, as may fairly 50 come within the spirit and scope of the same.

As mentioned, the front wheel 12 is of 55 relatively large diameter and as shown the same is positioned appreciably rearwardly of the front securing means 19. This construction insures that the greater part of the weight of the individual in following the natural movements while skating will be supported for the most part by the front wheel, the rear wheels being freed from contact with the floor and from having anything to do with the support of the individual by the slightest tilting of the foot. Therefore, in operation, especially high speed work, my skate is essentially a one 60 wheel skate. It is in such high speed work

that the extra size of the front wheel comes into play, in reducing bearing friction in the first place, as is the usual result of increasing the diameter of a wheel, and also in passing over without undue disturbance such ordinary unevennesses as are used for skating. the conditions being quite different from those found with skating on ice. With the higher elevation of the foot relatively to the point of support due to the larger diameter of wheel the tilting of the foot, either to effect the one wheel condition or the reverse, is more easily effected. The rear wheels would accordingly serve for the most part as supports for standing or under conditions other than high speed, and really serve as a drag or means for effecting extra friction, and for this reason are utilized for braking and stopping.

I claim as my invention:—

1. In a roller skate, a body frame for engaging with the foot, a set of rear wheels positioned below the rear portion of the said body frame, and a single front wheel, positioned below the said body frame, in front 85 of the said rear wheels, and appreciably rearwardly of the front end of the said body frame suitably to receive and sustain the greater part of the load supported by the said body frame, and the said front wheel 90 being of relatively large diameter.

2. In a roller skate, a sole member having a forked rear portion and a headed stud in front of the said forked rear portion, a heel member having a longitudinal slot for a portion of its length, the said stud being engaged with the said slot, and a clamping screw and nut serving to lock the said members together.

3. In a roller skate, a sole member having a forked rear portion and a headed stud in front of the said forked rear portion, a heel member having a longitudinal slot for a portion of its length, the said stud being engaged with the said slot, and a clamping 100 screw and nut serving to lock the said members together, and the said heel member having a cross-wise slot suitable to receive the free ends of the said forked rear portion.

4. In a roller skate a body portion and a 115 front heel lug, the said body portion having a headed stud and being provided with a longitudinal slot, the said heel lug comprising a piece of sheet metal having a main portion for engaging with the said body 120 portion and an upturned portion serving as the lug proper, the said main portion having a longitudinal slot suitable for receiving the said stud and having a hole for a clamping screw in registration with the said slot, 125 and the said heel lug having a cross-wise slot in the said upturned portion, connected with said longitudinal slot, and suitable to admit the head of the said headed stud.

5. In a roller skate, a wheel support of 130

U-shape, comprising a yoke and side arms, the said side arms having slots extending inwardly from the free ends, and a shaft for a wheel positioned in the said slots and secured to the said side arms, the free ends of the said arms being bent outwardly so as to overhang the body portion of the said arms and serving to prevent the removal of the said shaft from the said side arms.

10. 6. In a roller skate, a wheel support of U-shape, comprising a yoke and side arms, the said side arms having slots extending inwardly from the free ends, and a shaft for a wheel positioned in the said slots and secured to the said side arms, the ends of the said shaft overhanging the said side arms, and a wheel operatively mounted on each of the said ends of the shaft, and a spacing tube mounted on the said shaft, and positioned between the said arms.

7. In a roller skate, a pair of arms, a shaft extending through the said arms, a wheel on each end of the said shaft, a spacing tube mounted on the said shaft and positioned between the said arms, nuts engaged with the said ends of the shaft and serving to clamp the said arms to the said tube, and the said nuts having their outer faces

formed to serve as a raceway for balls for ball bearings.

8. A roller skate comprising a frame portion for engaging the foot composed of two members having overlapping portions, positioning and locking means for the said overlapping portions comprising a headed stud on one of the said members, the other of the said members having a longitudinal slot for engaging with the said stud, and the head portion of the said headed stud being elongated; having the longer dimension positioned transversely of the said one member; being of suitable dimensions to pass through the said slot when the said longer dimension is in registration therewith, and to overhang the walls thereof when out of such registration, whereby to disengage the said stud from the said slot in order to separate the said members it will be necessary to turn the said members relatively one to the other appreciably to one side of the position of longitudinal alinement.

EMERY E. HARDY.
